ELECTRIC MOUNT

Danforth W. Comins, Jr., Concord, Mass., assignor to Cambridge Thermionic Corporation, Cambridge, Mass., a corporation of Massachusetts

Application May 3, 1956, Serial No. 582,435

2 Claims. (Cl. 339—147)

This invention relates to mounts for electrical impedance means such as adjustable inductors or capacitors.

Objects of the invention are to provide devices of the above type which are especially suited for miniaturizing and for mounting on printed circuit panels to which they can be mechanically and electrically secured by dip soldering, to provide coil forms which are easily adaptable for various purposes and permit the mounting of an adjustable core, to provide devices of this type which can be easily and yet accurately and reliably assembled from pre-fabricated simple and inexpensive components, to provide coil forms which can be directly mounted as indicated above without requiring any special mounting components, and to provide devices of this type which are light, rugged in use and solidly constructed, but nevertheless inexpensive, and which are exceptionally strong and electrically and mechanically efficient, while requiring a minimum amount of molding, machining, and assembling operations.

Briefly stated by way of a summary indicating its nature and substance, devices according to the invention comprise a ring shaped collar although not necessarily toroidal, or annulus made of insulating material; a plurality of metal lugs which contact the inside of the collar which can have notches for that purpose, and have at one end a prong that extends radially thereof and at the other end a prong that extends essentially parallel to the axis of the collar; and a tubular insulating body, serving for example as a coil form, which at one end contacts with its outside, the inside of the terminal lugs. The lugs are preferably fastened to the collar by means of portions which are bent around the collar preferably within the above mentioned notches on the inside of the collar, and the insulating tube is forced into the inside of the collar and the lugs and preferably cemented in position. An impedance means such as a coil or an electrode can be mounted on the outside of the tube and an adjustable element such as an iron core or a second electrode can be adjustably mounted in the inside of the tube. The impedance component can be electrically connected to the radially extending lugs whereas the device as a whole can be mounted and electrically connected by means of the axially extending lugs for example by inserting them into perforations of a printed circuit board and fastening them thereto by way of dip soldering.

These and other objects and aspects of novelty of the invention will appear from the following description of a typical embodiment thereof illustrating its novel characteristics. This description refers to a drawing in which

Fig. 1 is a top elevation of an embodiment of the invention in the form of a coil form assembly;

Fig. 2 is a side elevation, partly in axial section, of the assembly according to Fig. 1;

Fig. 3 is an elevation of the annulus or collar which forms a base for the assembly according to the invention, also showing a section on lines 3—3 of Fig. 2 of one lug;

Fig. 4 is an axial section through the collar according to Fig. 3, and an elevation of lugs applied thereto, with

the left-hand lug prior to fastening and the right-hand lug after fastening to the collar; and

Fig. 5 is an axial section, with the coil form in elevation, through the completed assembly, indicating the mounting thereof on a printed circuit board.

The components of devices according to the invention are held together by a collar or annulus 11 which is made of insulating material such as a glass silicon or phenolic resin and which is generally speaking of rectangular cross section as shown in Figs. 2, 4, and 5, and which, in a preferred embodiment, has on its inside a number of notches for terminal lugs, indicated at 12.1, 12.2, 12.3, and 12.4 of Fig. 3. According to requirements, two or more notches are applied; in the present instance four such notches for terminal lugs are shown, but it will be understood that any desirable number can be used that can be accommodated, and that it does not necessarily have to be an even number.

The terminal lugs are initially made in the shape indicated at 15 of Fig. 4. Each lug has an axial prong 15.1, a shorter radial terminal prong 15.2, a rectangularly offset mounting portion 15.3 and a mounting tip 15.4 which extends at right angles from the prong 15.2 and is initially so dimensioned that the lug can be inserted in one of the notches 12.1 to 12.4 as indicated on the left-hand side of Fig. 3. The tip 15.4 is formed by angularly cutting out and bending a portion from the radial prong 15.2, thus leaving therein a recess 15.6 which also facilitates the soldering thereto of a wire. As shown in Fig. 2, the longer, axially depending prongs 15.1 have notches 15.7 and 15.8, serving similar purposes. After the lug portions 15.3 have been inserted in the notches 12.1 to 12.4 as shown at the left-hand side of Fig. 3, the arms 15.2 are bent such that the tips 15.4 engage the outer side of the collar 11, as indicated at 15.9 on the right-hand side of Figs. 2, 4 and 5. The lugs are now fastened to the collar so that this intermediate assembly can be easily handled.

After the lugs 15 have been applied to the collar 11 in this manner, the tube 17, for example a ceramic or spirally wrapped phenolic tube, with a thread 17.1 applied to its inside, is inserted with an end into the collar 11 and the lugs 15. As indicated in Fig. 2, the tube 17 is then cemented in position within the collar 11 and the lugs 15, the cement further securing the prongs as well as the tube to the collar 11.

As indicated in Fig. 2 at 17.1, the tube 17 has an inside thread embossed thereinto and this thread carries a tuning slug 17.2 whose position within the tube can be adjusted such as by means of a screwdriver slot 17.3. On the outside of the tube 17 is indicated a coil 17.5 constituting an inductance element. As indicated in Fig. 5, the ends 17.6 of the coil 17.5 can be brought towards and fastened such as by soldering to the radial prongs 15.9.

It should be understood that the present invention is not restricted to inductors of the type above described but could for example be adapted to capacitor devices with one plate on the outside and a second adjustable one on the inside of the tube 17.

Fig. 5 indicates the mounting of devices of this type on a printed circuit board indicated at *b* of Fig. 5 and carrying a printed metallic circuit indicated at *p*. The axially depending prongs 15 are inserted through holes of the panel, indicated at 18 of board *b* and the lugs or prongs 15 are then electrically and mechanically connected to the printed circuit *p* by means of dip soldering in well known conventional manner.

It should be understood that the present disclosure is for the purpose of illustration only and that this invention includes all modifications and equivalents which fall within the scope of the appended claims.

70 I claim:

1. A device for mounting electric impedance means,

comprising: a ring made of insulating material having a first and a second transverse end face respectively, inner and outer longitudinal surfaces, and longitudinal notches in said inner longitudinal surface; a plurality of metal lugs having portions extending longitudinally within said notches on said inner longitudinal surface and having first prongs extending radially on said first transverse end face of said ring and from there longitudinally in the direction of said outer longitudinal surface of the ring to form fastening and terminal members, and the lugs having additional prongs extending radially on said second transverse end face of the ring; and a tubular insulating form having a straight and smooth peripheral surface and a transverse end which conforms to the cross section of the form, the form extending with said transverse end into said ring with said peripheral surface substantially flush with said longitudinally extending portions of the lugs within the ring notches and with said inner longitudinal surface of the ring between the notches, and with said transverse end substantially flush with said first prongs where they extend radially on said first transverse end face of the ring; whereby said lugs are secured between the ring and the form.

2. A device for mounting electric impedance means, comprising: a ring made of insulating material having a first and a second transverse end face respectively, inner and outer longitudinal surfaces, and longitudinal notches in said inner longitudinal surface; a plurality of metal lugs having portions extending longitudinally within said
